UNITED STATES PATENT OFFICE.

GLEN PARKS, OF SEATTLE, WASHINGTON.

BOX-MAKING MACHINE.

Application filed September 15, 1926. Serial No. 135,597.

This invention relates to improvements in box making machines and more particularly to machines designed for assembling and nailing together the pieces making up the ordinary type of wooden box such as is in general use for packing and shipping apples.

It is the principal object of the present invention to provide a machine of the above character that will quickly and efficiently assemble, nail and deliver the boxes from the machine, which is not expensive to operate nor complicated in operation.

More specifically, the object of the invention resides in the provision of a box making machine including a frame structure and hoppers, or chutes, in which the pieces for forming the ends, bottom and side walls of the boxes may be stacked, means whereby these pieces may be delivered into the machine in assembled relation, means whereby the assembled parts may be nailed together and means for delivering the finished boxes from the machine.

A still further object is to so construct the various parts of the machine that they may be adjusted for the making of boxes of different size.

Other objects reside in the various details of construction and combination of parts embodied in the machine and in their mode of operation.

In accomplishing these and other objects of the invention, I have provided the improved details of construction, the preferred forms of which are illustrated in the accompanying drawings, wherein—

Figure 1 is a side elevation of a box making machine constructed in accordance with details of the present invention.

Figure 2 is the right end elevation of the machine as shown in Figure 1.

Figure 3 is a vertical section taken substantially on the line 3—3 in Figure 2.

Figure 4 is a vertical section taken transversely of the machine, substantially on the line 4—4 in Figure 3.

Figure 5 is a sectional view longitudinally of one of the nail drums showing also the nail picker and means for delivering the nails to the picker.

Figure 6 is a top view of the nail delivery means, the nail picker and tube whereby the nails are delivered from the picker to the nail driving mechanism.

Figure 7 is a cross sectional view through the nail drum.

Figure 8 is an end view of the same mechanism and a vertical, sectional view of the nail holder.

Figure 9 is a horizontal section on line 9—9 in Figure 8 showing the yieldable nail centering means and guide.

Figure 10 is a detail view of one of the stops on the head block which delivers the blanks to the nailing mechanism.

Figure 11 is a view illustrating the method of telescoping sections of the transverse shafts together to permit adjustment of the frame for boxes of different size.

Referring more in detail to the several views of the drawings—

All the mechanism of the machine is mounted upon a base or bed plate 1 provided about its periphery with a downwardly projecting flange 2 whereby the plate is held in spaced relation above the floor or foundation on which it is supported, and in this way, provides space beneath it for certain adjusting mechanism that presently will be described. Mounted on the base, at opposite sides, are the side frames 3 and 4 of the machine and these are supported vertically and in parallel relation and are adapted to be spaced apart various distances, according to the length of the boxes to be made in the machine.

Fixed to the opposite side frames, as best shown in Figure 2, are downwardly inclined chutes, or hoppers, 5 and 5^a in which the blanks, or pieces, designated at E, which are stacked on edge in such manner that they will feed by gravity downwardly along the chutes into position for advancement into the machine. At their lower, or inner, ends, along their lower edges, the chutes 5 and 5^a are equipped with upwardly projecting flanges 6 which serve as abutments against which the lower edges of the adjacent end pieces E will engage, and fixed to the frames 3 and 4 vertically above these flanges 6, are inwardly projecting, flanged guides 7 against which the upper edges of the pieces E engage. These two flanges 6 and 7 for each of the hoppers serve to support the two pieces, which are to form the ends of a box, in vertical, parallel relation and properly in position to be engaged by a reciprocating head block, presently described, which forwards them into the assembling and nailing mechanism.

The pieces designated at S which are to form one of the side walls of the boxes are

first stacked horizontally on a guide chute 8 fixed to the side frame 4, so as to extend horizontally therefrom, as best shown in Figure 2, and the bunch is then pushed, manually, 5 through a rectangular opening 9 in the frame 4 onto a pair of supporting rollers 10—10^a. The inward movement of the stack, or bunch, is limited by being brought against a pair of 10 vertical guides 11 of channel iron form fixed to the frame 3 and between which the stack may then be raised into position for advancement of the pieces S with the end pieces E, into the nailing mechanism.

The rollers 10—10^a which support the stack 15 of pieces S after the stack is moved into the machine, are horizontally mounted and support the stack at opposite ends. Each roller has trunnions at its ends mounted between the upper ends of the arms 12 of paired bell 20 cranks 13 fixed on shafts 14 which, at their ends, are pivotally mounted by brackets 14^a fixed to the side frames 3 and 4. The bell cranks are adapted to swing from and toward each other in vertical planes and the rollers 25 are urged upwardly at all times thereby, by means of a pair of coiled springs 15, which connect at their opposite ends with the lever arms 16 of the bell cranks at opposite sides of the frame. This provides for an automatic 30 upward feed of the stack of pieces S so that whenever the top blank, or piece, is advanced into the nailing mechanism, the stack is moved upwardly to position the next piece in position for advancement. Upward travel of 35 the stack is limited and the top piece properly positioned by abutment of its ends against the flanged inner ends 6 of the chutes 5 and 5^a. Whenever a stack of pieces S, carried on the rollers 10—10^a, becomes exhausted, the bell 40 cranks 13—13^a may be swung downwardly below the horizontal level of the chute, or guide, 8 and a new stack is moved into the machine and will be lifted into position by the rollers when the bell cranks are released. As a matter 45 of convenience for operating the bell cranks, the outer ones are equipped with handles 17 as shown in Figure 3.

The pieces which are to form the other side wall of the box are designated at S'. These 50 are stacked in a hopper formed by vertical guides 18—18' fixed to the inner walls of the side frames 3 and 4, as shown in Figures 2 and 3. The stack is supported at its opposite ends upon the guide flanges 7—7 and is disposed vertically above the stack of pieces S which are to form the other side of the box. There is a space, as at 19, between the lower 55 ends of the guides 18 and the supporting flanges 7—7 for the passage, or advancement, 60 of the pieces S' one at a time into the nailing mechanism.

The pieces B which are to form the bottom 65 walls of the boxes are stacked on edge in downwardly inclined guideways 21 mounted on top of the side frames 3 and 4. The stack

of pieces will feed downwardly by gravity to advance the ends of the lower end piece B against guides, or stops, 22 and there is a slight space, as at 23, between the stops and ends of guideways to permit the adjacent 70 piece B to be fed downwardly between them into the nailing mechanism.

The means employed for advancing pieces E, S and S' from their respective supply stacks into the assembling and nailing mechanism consists of a head block 25 that is reciprocally movable on a pair of horizontal, parallel shafts 26—26 fixed rigidly at their outer ends in bearings 27 formed in a cross piece 28 that adjustably joins the side frames 80 3 and 4 across one end of the frame, with their inner ends extending between the two supply stacks of pieces E and pieces S and S'. The head block has plates 29—29' fixed adjustably by bolts 30 to its opposite ends and each of 85 these plates has a pair of inwardly yieldable stops 31 mounted thereon which are adapted, when the head block moves inwardly, to engage with the outer edges of the adjacent end pieces E to cause the latter to be advanced 90 therewith into the nailing mechanism. On outward movement of the head block, the stops yield inwardly when engaged with the stacks but snap out when they are disengaged therefrom, so as to be in proper position for 95 engaging the next pieces when the head again moves inwardly. These stops, as shown in Figure 10, are limited in their outward movement by suitable stops as at 32, and are urged outwardly by coiled springs 34 pressing upwardly thereagainst.

Likewise plates 35—35' are fixed adjustably by bolts 36 to the upper and lower edges of the head block and these are provided at 105 their outer edges with yieldable stops 31 for engaging the edges of the adjacent pieces S—S' to advance them into the nailing mechanism simultaneously with the end pieces E.

The means whereby the head block 25 is reciprocated comprises a link 40 that is pivotally connected, at its inner end, as at 41, to the head block and, at its outer end, has pivotal connection, as at 42, with the upper end of a lever 43 that is pivotally fixed at its lower end to the base 1. A motor driven shaft 45 extends horizontally through the side frames 3 and 4 within suitable bearings provided in said frames and keyed on this shaft adjacent the outside of the frame 3 is a gear wheel 47 provided in its inner surface with a cam slot 48. A lever 49 is pivotally fixed, at its lower end, to the frame, see Figures 1 and 2, and, at its upper end, has a roller 50 thereon contained within the cam slot 48 and a link 51 connects lever 49 and lever 43 so that, as the cam rotates, the head block is reciprocated.

The means for feeding the bottom pieces B from their hopper into the nailing mechanism comprises a pair of reciprocal feed blocks 54 that are slidable in guide grooves 22' formed 130

longitudinally in the stop strips 22 against which the lower end of the stack of pieces B rests. Each of these blocks is equipped with inwardly yieldable latches 55 of the same character as those previously described on the head block which engage with the upper edge of the inner piece B as said blocks move downwardly to cause the piece to be advanced downwardly into the machine. The blocks 10 are reciprocated together by means of levers 56 which have ends pivotally connected thereto, as at 57, and which have a slideable and pivotal connection at their outer ends, as at 58, with a cross shaft 59 extended between the 15 side frames 3 and 4. Pivotally connected with each of the levers 56 are the upper ends of rods 60 which, at their lower ends, have longitudinally extended slots 61 through which the driven shaft 45 extends. Cam wheels 20 62-62 are fixed on the shaft and these have cam slots 62' in which rollers 63 mounted on the lower ends of rods 60 are adapted to follow as the cams revolve so as to cause the rods to be reciprocated and the feed blocks 25 actuated accordingly.

The parts which actuate the head block 25 and those which actuate the feed blocks 54 are so synchronized that the bottom pieces B are fed into the machine just in advance of the 30 ends, E, and opposite side pieces and the latter will then engage with and serve to advance the bottom piece B, as is indicated in dotted lines in Figure 3, into nailing position.

The parts, or mechanism, into which the 35 pieces are advanced and whereby they are held in assembled relation and nailed together are as follows: Formed in the opposite side frames 3 and 4 in horizontally aligned relation are circular openings 65-65' and 40 revolvably fitted in these are the hub portions 66 of circular plates 67-67' which form the opposite ends of a frame in which the pieces making up a box are held during the nailing operation. The plates are disposed 45 adjacent the inner faces of the side frames and the hub flanges extend outwardly through the openings and have gear wheels 68-68' fixed thereon. A shaft 69 extends transversely between the side frames and this has gear wheels 50 70-70' fixed on its opposite ends in mesh with the gears 68-68' so that the gears and plates 67-67' will rotate together and will maintain the same relative position with respect to each other during rotation. The plate 67 has 55 a gear wheel 73 fixed coaxially within its hub portion adapted to be driven intermittently by means of a gear 75 fixed on the driven shaft 45, see Figures 1 and 4. The gears are so proportioned that the gear 73 makes one complete revolution to approximately one half revolution of the gear 75 and then remains 60 still while gear 75 completes its revolution.

Fixed on the inner sides of each of the circular plates 67-67' in parallel relation 65 are upper and lower supporting guide rails

76 and 77 and extending between ends of the parallel rails, as shown in Figure 3, is a stop rail 78. These rails are transversely slotted, as at 79, and have supporting bolts 80 extended through said slots to adjustably secure the 70 rails to the plates for adjustment from and toward each other according to the size of box being made.

When the end plates 67-67' are at rest the parts carried thereon are positioned, as 75 shown in Figure 3, so that when the cross head 25 which is actuated inwardly during this period of rest of the end plates, it will advance the ends, sides and bottom pieces of a 80 box into the frame where they will be held in properly assembled relation for nailing; the bottom piece B being disposed against the stop rails 78, the upper and lower sides S and S' being disposed respectively against the rails 76 and 77 and the end pieces E against 85 the inner faces of the opposite end plates and within the ends of the side and bottom wall pieces. After the head block has been advanced inwardly to so position the parts of 90 the box and has been withdrawn, the whole structure supporting the box is bodily rotated by action of the intermittent gear; rotation being in the direction indicated by the arrow in Figure 1.

The nailing of the parts together is effected 95 during rotation of the box in the following manner: Each of the rails 76-77 and 78 is provided with a plurality of holes 84 (See Fig. 8) leading from their outer sides to their 100 inner sides into which nails may be delivered in proper relation for nailing the side and bottom pieces to the ends of the box. Nail delivery tubes 85 lead into these holes at the inner sides of the blocks and the tubes extend outwardly radially with respect to the 105 axis about which the parts rotate, and, during rotation, they pass successively beneath a nail picker, presently described, which operates to deliver a nail into each tube.

Slidably contained in each of the holes 84 and extending outwardly therefrom, are plungers, or hammers, 86 for driving the 110 nails. The several hammers of each set are fixed rigidly, at their outer ends, to cross heads 87 and each cross head is provided centrally on its outer side with a roller 88 adapted to follow within cam grooves 89 formed within rings 90 fixed about the plates 67-67' to the end frames. The cam grooves are of 115 such form, as shown best in Figure 3, that as the plates rotate, the cross heads will be actuated inwardly a sufficient distance that the plungers, or hammers, will drive the nails into the box ends. The nail driving mechanisms for the two ends of the box are identical but are fed from separate nail supply containers and nail pickers.

The nails for the opposite ends of the boxes are contained in a pair of horizontally disposed and parallel drums 95-95' which are 120

rotatably supported upon rollers 96 carried by the arms 97 of a supporting structure 98 fixed to the frame of the machine. The outer ends of the drums have centrally located openings 99 through which nails may be placed within the drums and fitted within the inner ends of the drums are rings 100 which serve to keep nails from working therefrom. A plurality of ribs, or rails, 101 are fixed longitudinally within the drums to serve as scoops for raising the nails up and pouring them into belts whereby they are carried from the drums to the nail pickers. The belts operate in the longitudinal direction of the drums 15 through their open ends and are carried by means of belt wheels 103 mounted at the inner ends of arms 104 that extend from the frame into the drums and about wheels 105 forwardly of the drums carried by a cross shaft 106 that also is revolvably supported between the arms 104. Each of the nail carrying belts consists of a pair of parallel wires 107—107' spaced apart just a little more than the diameter of a nail so that when the nails 20 are poured onto the belts incidental to rotation of the drums, some of the nails will be suspended by their heads, as shown in Figures 5 and 6, between the parallel wires and will be carried thereby from the drum and delivered into chutes 108—108' whereby they are fed to the nail pickers.

The means provided for revolving the nail supply drums consists of a belt 110 which operates about the two drums and about a belt wheel 111 on a horizontal shaft 112, carried by brackets 113—114 mounted on the base 1 and driven gears 115 and 116 fixed respectively on the shaft 112 and 45. The belts which deliver the nails to the pickers are 40 driven by means of a belt 118 that operates about a belt 119 on shaft 112 and a belt wheel 119' on the shaft 106.

The nail pickers whereby nails are delivered one at a time from the chutes 108—108' 45 into the nail delivery tubes 85 as they pass the pickers comprise wheels 120 that are freely revolvable on the ends of a shaft 121 extended between the arms 104. Each wheel is formed with a plurality of equally spaced, 50 laterally bent wings 123 each equipped with a projecting stud 124 adapted to be engaged by the outer end portion of a nail delivery tube as it passes the wheel to thereby rotate the picker wheel in such manner that the 55 wing will engage with and pick off one nail from the end of the adjacent chute and will cause the nail to drop into the tube and be delivered into the opening below the hammer member in position for being driven into the box. Thus, as each nail tube passes the 60 picker it causes a nail to be delivered thereinto.

The nails are held in their respective openings 84 by centering balls 125, as shown in 65 Figs. 8 and 9, the balls being contained in

horizontal bores 126 and pressed inwardly by springs 127 toward the center of the hole so as to center the end of the nail in the hole but are yieldable outward to permit the nail to be advanced past them by the plunger or 70 hammer 86.

After the parts for making a box have been delivered into the nailing mechanism and the latter has been revolved therein to effect the nailing operation, the rotative movement 75 stops and the box is delivered, from the machine. This is accomplished by the reciprocal action of a push rod 130 that is slidably mounted in a bearing 131 formed centrally in the gear 73, as shown in Figure 4. At its 80 inner end, the push rod has a head plate 132 adapted to engage with the end of the box and, at its outer end, has a pin and slot connection, as at 133, with the upper end of a lever 134 that is pivotally fixed, at its lower end, to the base plate 1, as at 135, and is oscillated by means of a link 136 having its outer end pivotally fixed thereto by a pin 137 and having its inner end fixed by a ball and socket connection 138 with one end of a lever 139 that is pivotally mounted by a bolt 140 on the base 1 and has its other end equipped with a stud 141 that operates in a cam groove 142 of a wheel 143 fixed on the drive shaft 45.

The parts are so synchronized that the plunger is actuated inwardly immediately when the box stops rotating and it delivers the box endwise through the opening 145 in the plate 67'. The plunger is then quickly drawn back and out of the way before the head block moves inwardly to deliver the blanks for the next box.

Since the side of the frame, or plate, 67' is provided with an opening for the discharge 105 of the boxes which is somewhat larger than the dimensions of the box, it is apparent that provision must be made for supporting the box ends at that side so that they will not fall outwardly through the opening before 110 they are nailed to the side and bottom pieces. This is accomplished by means of slides 146 which are slidably supported from the plate 67' so that they may be moved into and from the opening as supports for the box ends. These slides are normally disposed in position as shown in Figure 4 so as to support the ends E but are automatically actuated outwardly upon the initial inward movement of the discharging push rod 130. The means whereby this is accomplished, as 115 shown best in Figure 4, comprises bell cranks 148 that are fixed pivotally to the base of gear 73 and have arms 149 provided with ball shaped ends 150 seated in a groove 132' formed in the hub portion of head 132 on the rod and have other arms 151 connected with the ends of rods 153 that extend transversely of the machine and connect to levers 154 on shafts 155 supported from the rails 76, 77 and 120 125 130

78. These shafts have other arms 156 fixed thereto and extended through slots in the rails and operatively connected to the slides 146. Coiled springs 158 are wound about the 5 rods 153 and bear against collars 159 thereon and against the ends of tubular housings 160 enclosing the springs, and fixed to the end plate 67 so that the action of the springs yieldably urges the rods to move the slides 10 to open position. However, when the push rod 130 has been moved inwardly to the position as shown in Figure 4, the head 132 contacts with the ball ends 150 of arms 149 of bell cranks 148 and this actuates the bell 15 cranks, so as to move the slides into position to hold the ends E in place for nailing.

In order that boxes of different length may be made in the machine, the side frames are supported for adjustment from and toward 20 each other. The side frame 3 is fixed solidly to the base but the frame 4 is provided with depending lugs 160 projecting through slots in the base plate. Threaded shafts 162 extend transversely below the base and are 25 revolvably mounted at their ends in bearings 163 formed on the base supporting flanges 2. The threaded portions of these shafts extend through the lugs 160 so that rotation of the shafts causes the frame 4 to be moved toward or from frame 3. In order that both 30 shafts may be rotated together, they are equipped with sprocket wheels and sprocket chains 165 extended about the wheels, and the ends of the shafts are extended from the 35 side of the base and are constructed to receive a wrench, or the like, whereby they may be rotated.

In order to permit of this adjustment of the side frames, all connecting shafts between the frames, such as shafts 45, 69, 106, and 153 are of a telescopic character as shown in Fig. 11 and automatically adjustable with the side frame.

Assuming that the machine is so constructed, its operation is as follows:

A supply of end blanks E is placed in each of the hoppers 5—5^a, a supply of side blanks S is moved into the machine for support on rollers 10—10^a, a supply of opposite side blanks S' is placed in the guides 18—18' and a supply of bottom blanks B is placed in guideways 21. Then, as the machine starts operation, by rotation of drive shaft 45, cam 47 through connecting link 51, causes oscillation of lever 43 and a resultant inward reciprocal movement of cross head 25 whereby one set of end blanks and opposite side blanks are advanced inwardly. Synchronized with this operation, the levers 56 are oscillated by 50 the rods 60 connected with cams 62—62, to feed a bottom blank B downward for advancement by the ends and side blanks. Inward movement of the blanks into the nailing mechanism where they are held in assembled relation by the rails 76—77 and 78 is effected by inward movement of the cross-head 25. As the cross head 25 moves outwardly, the nailing mechanism starts to rotate and during rotation thereof, the several sets of hammers are actuated inwardly 70 through their connection with cams 89 and the nails driven to fasten the side and bottom blanks to the end blanks. After one complete revolution, the nailing mechanism comes to rest, in the position as shown in Figure 75 3, and the plunger 130 is actuated inwardly to discharge the box, then the cross head 25 is again actuated inwardly to advance another set of blanks into the machine and the operation is repeated.

Having thus described my invention, what I claim as new therein and desired to secure by Letters-Patent, is:

1. In a box making machine, in combination, a plurality of hoppers for containing supplies of box forming parts, a nailing mechanism comprising a revolvably mounted frame, nail holding means and hammers, means for advancing the pieces for forming a box from the several hoppers in assembled relation into the frame of the nailing machine, means for rotating the latter, means operable incidental to such rotation for actuating the hammers to nail the parts together, and means operable to discharge the box from the frame after nailing.

2. In a box making machine, in combination, a nailing device comprising a frame wherein parts of a box may be held in assembled relation and nailed together, a guide way, a rectangular head block reciprocally movable in said guide way, hoppers arranged above, below and at opposite sides of the path of travel of the head block for containing the ends and side pieces of boxes, another hopper above the path of travel for containing the bottom pieces of boxes, dogs on the edges of the head block adapted on inward movement of the block to engage with and advance end and side pieces from their hoppers along the guide way into the nailing device, and a feed block synchronized with movement of the head block for delivering bottom pieces into the path of travel of the ends and sides so as to be advanced thereby and in proper assembled relation therewith into the nailing device.

3. In a box making machine, in combination, a nailing device comprising a frame wherein the parts of a box may be held in assembled relation and nailed together, a pair of guide shafts, a rectangular head block slideable on said shafts, hoppers arranged above, below and at opposite sides of the path of movement of the head block for containing the ends and sides of boxes, another hopper above the path of the head block for containing bottom pieces of boxes, means on the head block operable, on each inward movement thereof, to engage and advance one set of box

- forming pieces from the first mentioned hoppers into the nailing machine, a driven shaft, means operated by said shaft in synchronism with the feed block to deliver bottom pieces singly into the path of the head block so that they will be advanced in assembled relation with the side and end pieces into the nailing device, and means on said shaft for actuating the head block.
- 10 4. In a box making machine, in combination, a frame structure, a plurality of hoppers for containing supplies of box forming pieces, a nailing mechanism comprising a revolvably mounted frame, nail holders and hammers, means for intermittently revolving the frame, a reciprocating head operable by each inward movement to deliver the parts for a box in assembled relation into the revolvble frame while it is at rest, means operable incidental to rotation of the frame for actuating the hammers to drive the nails to secure the parts of the box together, and a reciprocally operable plunger for delivering the box from the frame.
- 15 5. In a box making machine, a frame structure, a head block mounted for horizontal reciprocation within the frame, hoppers at opposite sides of the frame for containing supplies of box end pieces adapted to feed toward the path of movement of the head block, a hopper above the path of movement of the head block for containing a supply of box side pieces, a hopper below the path of the head block for containing a supply of the opposite side pieces, another hopper above the path of travel of the block for box bottom pieces, a nailing mechanism, a driven shaft, means connected with the shaft for reciprocating the head block, means operatively connected with the shaft for feeding bottom pieces from their hopper into the path of travel of the head block, means on said block engageable with box forming end and side pieces to advance them from their hoppers in assembled relation with a bottom piece into the nailing mechanism, and means for actuating the latter to nail the parts together and to discharge the box from the machine.
- 20 6. In a box making machine, a frame, a nailing mechanism, a head block mounted for horizontal reciprocation in said frames into and from the nailing mechanism, hoppers at opposite sides of the path of travel of the head block for containing supplies of box end pieces, stops at the inner ends of said hoppers for supporting the pieces, a hopper above the path of the head block for containing a supply of box sides and a hopper below for containing a supply of the opposite side pieces, means for feeding the latter upwardly as used from the hopper, another hopper above the path of the block for containing a supply of box bottoms, a driving shaft, a feed block operatively connected with the shaft for delivering the said bottoms singly into
- 25 the path of the head block, means operatively connecting the shaft and head block to reciprocate the latter, yieldable dogs on the head block adapted to engage and advance box ends and sides with their bottom piece into the nailing mechanism, means for actuating the latter to nail the parts together, and a plunger operable to discharge the box from the machine.
- 30 7. In a box making machine, a nailing mechanism comprising a revolvble frame open at one side and at one end, means for delivering box forming pieces in assembled relation into the frame at the open side thereof, means for nailing the parts together within the frame, and means for discharging the box from the open end of the frame.
- 35 8. In a box making machine, an intermittently revolvble frame open at one side and at one end, means in said frame for supporting box forming parts in assembled relation, means for delivering said parts thereto during a period of rest of the frame, nailing means carried by the frame and operable incidental to rotation thereof to nail the box parts together, and a plunger operable to discharge the box from the frame through the open end thereof.
- 40 9. In a box making machine, in combination, a nailing device, means for delivering the forming parts into said nailing device in assembled relation and means for actuating the nailing device to nail the parts together; said nailing device comprising a frame open at one end, means at said open end for supporting the adjacent box forming piece prior to its being nailed, a plunger operable to discharge the finished box through said open end, and means for removing said supporting means to permit passage of the box.
- 45 10. In a box making machine, in combination, a nailing device, means for delivering box forming parts into said nailing device in assembled relation and means for actuating the nailing device to nail the parts together; said nailing device comprising a frame open at one end, means at said open end for supporting the adjacent box forming piece prior to its being nailed, a plunger operable to discharge the finished box through said open end, and means operated by actuation of the plunger for removing said supporting means to permit the discharge of the box through said open end.
- 50 11. In a box making machine, in combination, a nailing device comprising a frame open at one side and at one end, rails fixed in said frame whereby the parts of a box may be held in assembled relation, means for delivering box forming pieces through said open side of the frame into said frame in assembled relation, a pair of adjustable members for supporting the end forming piece of a box adjacent the open end of said frame prior to its being nailed to the other pieces,

- means for actuating the nailing device to nail the parts together, a reciprocally movable plunger engageable with the box to discharge it through the open end of the frame, means 5 operable by initial movement of the plunger for removing said adjustable supporting members from the path of travel of the box, and means for resetting them in functional position on return of the plunger.
- 10 12. In a box making machine, a frame, means for supporting supplies of box forming pieces, a nailing mechanism comprising a revoluble frame, mechanism for delivering box forming pieces in assembled relation in 15 to said frame, nail holders, a nail supply device, means for feeding nails from said supply device into said holders, hammers for driving the nails, and means for actuating the hammers.
- 15 13. In a box making machine, a nailing mechanism comprising an intermittently rotatable frame open at one side, means for containing supplies of box forming pieces, means for delivering pieces therefrom in as 20 sembed relation into said frame at the open side, nail holders carried by the nailing mechanism, a nail supply device for delivering nails into said holders, hammers carried by the frame for driving the nails delivered into 25 the holders, means for rotating the frame, and means operable incidental to such rotation for actuating the hammers to drive the nails.
- 20 14. In a box making machine, an intermittently revoluble frame, means in said frame 30 for supporting box forming pieces in assembled relation, means for delivering box forming pieces thereto during its periods of rest, nail holding devices, means for feeding nails to the holders, hammers carried by the frame 35 to drive the nails, a fixed cam encircling the frame, and means connecting the hammers with the cam whereby the latter will be actuated incidental to rotation of the frame.
- 35 15. In a box making machine, an intermittently revoluble frame, open at one side and end, rails in said frame for supporting box forming pieces in assembled relation, means for delivering box forming parts thereto during 40 periods of rest of said frame through the open side thereof, nail holders carried by said rails, a nail supply, means for delivering nails from said supply into the holders as they revolve with the frame, hammers carried by the rails for driving said nails, a cam 45 encircling the frame, means connecting the
- hammers and cam whereby the hammers will be actuated to drive the nails as the frame revolves, and means for discharging the box from the open end of the frame at the completion of the nailing operation. 60
- 50 16. In a box making machine, a plurality of hoppers for containing supplies of box forming parts, a nailing device comprising a revolubly supported frame open at one end, 65 means for intermittently rotating the frame, a reciprocally movable head block adapted to advance box forming pieces from the supply hoppers into the nailing frame, rails fixed in the frame for supporting the parts of the 70 box in assembled relation during nailing, nail holders in said rails, a nail supply device, means for delivering nails into the holders from the supply device, hammers carried by said rails for driving the nails, fixed cams 75 encircling the frame of the nailing device, cam followers connected with the hammers for actuating the latter incidental to rotation of the frame, a plunger operable in the axial direction of the frame for discharging the boxes therefrom at the end of the nailing operation, and means for synchronously actuating the head block, the nailing device and plunger. 80
- 80 17. In a box making machine, in combination, a nailing device comprising revolubly supported, opposite end frames, rails fixed to the inner faces of said frames whereby parts of a box may be held in assembled relation, nail holders in said rails, hammers carried by said rails, gear wheels fixed to said end frames, a cross shaft, gears on said shaft meshing with the first gears whereby said end frames are rotated together, a driving gear fixed to one of said frames, a driven 85 shaft, an intermittent gear on said shaft, adapted to mesh with the driving gear to intermittently rotate the end frames, means operated by said driven shaft for delivering box forming parts into the frames of the nailing device in assembled relation during 90 periods of rest, fixed cams encircling the end frames, cam followers adapted to actuate the hammers to nail the parts together during rotation of the frames, and a plunger operatively connected with the driven shaft and operable in the axis of rotation of the nailing device to discharge the boxes after the 95 nailing operations. 100
- 100 Signed at Seattle, Washington, this 26th day of August, 1926. 110
